(57) **CLAIM**

The ornamental design for paperboard container with flip-top lid, as shown and described.

DESCRIPTION

FIG. 1 is a top plan view of a paperboard container with flip-top lid in accordance with the present invention, showing the lid in its closed position.

FIG. 2 is a bottom plan view of the paperboard container with flip-top lid of FIG. 1.

FIG. 3 is a right side elevation of the paperboard container with flip-top lid of FIG. 1.

FIG. 4 is a left side elevation of the paperboard container with flip-top lid of FIG. 1.

FIG. 5 is a front elevation of the paperboard container with flip-top lid of FIG. 1.

FIG. 6 is a rear elevation of the paperboard container with flip-top lid of FIG. 1.

FIG. 7 is a top, front perspective view of the paperboard container with flip-top lid of FIG. 1.

FIG. 8 is a top view of a paperboard container with flip-top lid in accordance with the present invention, showing the lid in its open position.

FIG. 9 is a bottom view of a paperboard container with flip-top lid of FIG. 8.

FIG. 10 is a right side elevation of the paperboard container with flip-top lid of FIG. 8.

FIG. 11 is a left side elevation of the paperboard container with flip-top lid FIG. 8.

FIG. 11 is a left side elevation of the paperboard container with flip-top lid of FIG. 8.

FIG. 13 is a rear elevation of the paperboard container with flip-top lid of the FIG. 8.

FIG. 14 is a rear perspective view of the paperboard container with flip-top lid of FIG. 8.

FIG. 15 is a top, front perspective view of the paperboard container with flip-top lid of FIG. 8.

FIG. 16 is a top plan view of a flip-top lid in accordance with the present invention, showing the lid in a closed orientation.

FIG. 17 is a bottom plan view of the flip-top lid of FIG. 16.

FIG. 18 is a right side elevation of the flip-top lid of FIG. 16.

FIG. 19 is a left side elevation of the flip-top lid of FIG. 16.

FIG. 20 is a front elevation of the flip-top lid of FIG. 16.

FIG. 21 is a rear elevation of the flip-top lid of FIG. 16.
FIG. 22 is a top, front perspective view of the flip-top lid of FIG. 16.
FIG. 23 is a bottom perspective of the flip-top lid of FIG. 16.
FIG. 24 is a top plan view of the flip-top lid of FIG. 16, shown in its open orientation.
FIG. 25 is a bottom view of the flip-top lid of FIG. 24.
FIG. 26 is a left side elevation of the flip-top lid of FIG. 24.
FIG. 27 is a right side elevation of the flip-top lid of FIG. 24.

FIG. 28 is a front elevation of the flip-top lid of FIG. 24.
FIG. 29 is a rear elevation of the flip-top lid of FIG. 24; and, FIG. 30 is a top, front perspective view of the flip-top lid of FIG. 24.

The flip-top lid is shown separately in FIGS. 16-30 for clarity of illustration.
